UNITED STATES PATENT OFFICE.

HENRY M. KINPORTS, OF BOSTON, MASSACHUSETTS.

DESIGN FOR A CHAIR.

SPECIFICATION forming part of Design No. 26,207, dated October 20, 1896.

Application filed September 11, 1896. Serial No. 606,537. Term of patent 3½ years.

To all whom it may concern:

Be it known that I, HENRY M. KINPORTS, of Boston, in the county of Suffolk and State of Massachusetts, have invented a new and original Design for Rattan or Wicker Chairs, of which the following is a specification, reference being had to the accompanying drawing, showing a part thereof.

The figure of the drawing is a perspective view of a rattan or wicker chair, showing my design.

The leading features of my design consist in the outwardly-curved horn-like terminals or upper ends of the side rolls; the extended pike-like terminals of the upright standards of the back; the downwardly-curved head-rest between the upright standards, and the arches at the sides of the seat forming the legs, with the parallel bars between the front and rear legs and the vertical spindles between the said parallel bars.

S designates the chair-seat, which is of general contour.

L are the legs, consisting of arches at the sides of the seat, with parallel bars *a a* between the front and rear legs and vertical spindles *s* between the said parallel bars.

R designates the side rolls forming the arms

and outer edges of the back, the upper ends *b* of which rolls are curved outwardly and 30 terminate in somewhat pointed knobs *c*, so as to have a horn-like appearance.

B is the back proper between the upwardly-projecting portions of the side rolls. At the sides of the back are the upright standards 35 *U*, which terminate at their upper ends with somewhat sharpened pike-like knobs *d*.

H is the head-rest between the upright standards, which curves downward from the knobs *d* and standards *u*. The connections 40 between the side rolls and upright standards are of scroll-like contour, or may be given other shape, as desired.

What I claim is—

The design for rattan or wicker chairs substantially as hereinbefore shown and described.

In testimony whereof I have signed my name to this specification, in the presence of two subscribing witnesses, this 4th day of August, A. D. 1896.

HENRY M. KINPORTS.

Witnesses:

ARTHUR W. CROSSLEY,
C. C. CATE.
